DESIGN FOR A GAME BOARD

James Mason Prentice, Holyoke, Mass.

Application January 27, 1939, Serial No. 82,626

Term of patent 3½ years

To all whom it may concern:

Be it known that I, James Mason Prentice, a citizen of the United States of America, residing at Holyoke, in the county of Hampden and State of Massachusetts, have invented a new, original, and ornamental Design for a Game Board, of which the following is a specification, reference had to the accompanying drawing, forming part thereof.

The drawing is a plan view of the game board, showing my new design. The game board is flat, having no substantial thickness, and the game features illustrated in the drawing are flush with the surface.

I claim:

The ornamental design for a game board, substantially as shown and described.

JAMES MASON PRENTICE.
